UNITED STATES PATENT OFFICE.

ROBERT J. KEE, OF TORONTO, ONTARIO, CANADA.

LIFE-SAVING DEVICE AND APPLIANCE.

1,281,975.

Specification of Letters Patent. Patented Oct. 15, 1918.

Application filed February 23, 1918. Serial No. 218,821.

To all whom it may concern:

Be it known that I, ROBERT JOHN KEE, subject of the King of Great Britain, residing at 276 Roncensvalles avenue, in the city of Toronto, in the county of York and Province of Ontario, Canada, have invented new and useful Improvements in Life-Saving Devices and Appliances, of which the following is a specification.

10 My invention relates to improvements in life saving devices and is primarily intended for the use of those at sea.

Life belts and other similar devices provided for passengers and others on ship-board do not answer all requirements as they only serve to sustain the wearer in the water, so that if the person wearing the device is in the water for a prolonged period, his health will be injuriously affected 20 and he will probably succumb to cold and hunger.

My invention consists in the provision of a suit of suitable waterproof material adapted to cover the wearer from head to foot, and is supplied with a series of air-chambers which are preferably arranged vertically around the body, legs and top, back, and sides of the helmet. The latter is provided with a look-out of plate glass or other suitable material, and an air inlet opposite the nose and mouth which may be opened and closed at the will of the wearer; the front of the helmet from the forehead down is well arched outward by means of 30 stiffening ribs of whalebone or other preferred material so as to provide ample room for moving the hands in front of the face.

The inside of the suit is lined with wool or other warm material, and is provided with pockets; an air pump may also be supplied for inflating the body air chambers, which latter are in that case connected by means of piping to the said pump, or said body chambers may be inflated by blowing 45 into a tube connected to said chambers and terminating in the helmet. In either case non-return valves are arranged on each air chamber, and I prefer to employ a check valve also between the said non-return valves and the trunk air line so that in the event of one chamber becoming defective the utility of the others will not be impaired.

The leg air chambers have tubes attached which terminate in the helmet, so that the

said air chambers may be inflated by blowing into the said tubes, the ends of which are provided with suitable valves.

The inflation and deflation of the helmet air chambers is controlled in the same way as the leg air chambers.

An opening is provided in the upper portion of the suit which is secured both inside and out as I prefer to reinforce the closure with a waterproof roll on the inside.

One of the objects of my invention is to 65 provide a suit which, deflated, may be worn on board a vessel, and which is not too heavy to work in.

Another object of my invention is to supply a suit which may be quickly rendered 70 unsinkable by pumping or blowing air into the air chambers, the said air chambers and piping being so arranged that some of the said chambers may be inflated or deflated independently of other of the said chambers.

75 A further object of my invention is to construct a suit in which the wearer may be thrown into the water with a minimum risk of injury, and in which life may be sustained for a considerable period if the 80 pockets have previously been filled with sustenance.

With these and other objects in view my invention consists in certain novel constructions and combinations of parts fully 85 described with the aid of the accompanying drawings in which similar parts are similarly designated in all the views.

Figure 1 shows a front elevation of my suit.

Fig. 2 a partial elevation with the inner closure fastened, and the outer one open.

Fig. 3 is a section on the line 3—3 of Fig. 1.

Fig. 4 is a non-return valve.

Fig. 5 a detail of the air inlet in the helmet.

Fig. 6 an elevation of the upper portion of the suit as worn on board ship with the inner and outer closures open and the upper 100 portion of the suit hanging in front of the wearer.

Fig. 7 is a detail of a sleeve.

Fig. 8 is a detail showing one of the sleeves.

Fig. 9 is a detail of the air inlet pipe.

Figs. 10 and 11 are side and end views of the end closures for the air inlet pipe.

Figs. 12 and 13 are detail views of the non-return valves on the ends of the body air chamber pipes.

Fig. 14 is a detail showing a clasp which is placed on the air pipes, when the chambers to which said pipes lead, become defective. These clasps prevent air from entering into the defective chambers.

Referring more particularly to the drawings, 1 designates the body of my suit, the outside of which is made up of vertical air chambers 2, and secured exteriorly by means of fastenings 3, and interiorly by fastenings 4. The legs 5, and boots 6, are preferably integral with the body 1, as also are the sleeves 7 and gloves 8. The said boots and gloves are preferably of ordinary rubber. Each leg 5, has one air chamber encircling same, and, although the said air chambers are ribbed or quilted so as to provide a corrugated surface to the water, each division or corrugation is connected to each adjoining division or corrugation so that the whole may be inflated or deflated through 25 the tubes 9 and valves 10.

Similarly the helmet 11 has one large air chamber 12 covering the top, back, and sides, and though ribbed or quilted as shown at 16, the whole may be inflated or deflated 30 through the valve 14 and tube 13.

The valves 10 and 14 are identical, and preferably include a head 15 adapted to close against the seat 17 when air pressure from within the tubes 9 and 13 forces the head 15 outward. The said head 15 is held 35 in closed position by means of the spring 18, one end of which is secured to the valve head 19, and the other end to the ring 20 arranged on the inside of the valve body 40 10 or 14. When the air chamber is being inflated the air pressure overcomes the pressure of the spring 18 and passes into the tubes 9 or 13. In order to deflate the air chamber a slight inward pressure on the end 45 42 of the valve 15 will raise the said valve from its seat and permit the air to escape. But instead of using the above described type of valve I may when desired substitute another of suitable design without deviating from within the limits of my invention.

The front of the helmet 11 is provided with a signal flag 38 to attract the attention of passing vessels, a transparent look-out 55 21, and an air inlet 22. The latter consists of a pipe having a longitudinal slot 23 covered with gauze or other suitable material.

The ends of the pipe are supplied with spring actuated ends 24. The springs 25 60 tend to keep the said ends 24 in open position but when the cords 26 are pulled in the direction of the arrows 27 the ends 24 are closed and air no longer admitted. Slides 28 attached to the ends 24 are supported 65 in guides 29. (It will be understood that the

pipe is located within the helmet and in operation air enters the aperture 23 and passes laterally through the open ends of the pipe and into the helmet. When, however, it is necessary to close the open ends of the pipe, 70 the operator pulls the cords 26 downwardly and this draws the ends 24 into closed position.) The front of the helmet 11 is arched in front from the forehead to the breast by ribs 37, to facilitate the movement of the 75 wearer's hands.

A woolen or other warm lining 30 is provided inside the suit 1, the body of which is supported within by suspenders 31. The latter are particularly useful when both closures are unfastened and the helmet thrown back, and the wearer's head and shoulders exposed as shown in Fig. 6.

It will be noted from Fig. 8 that the underside 41 of the sleeves 7 are joined 85 to the body portion 1 about the wearer's elbow and are reasonably close fitting from the elbow down, so as to allow ample room for inserting or removing the arm, and at the same time to permit of easy movement 90 of the hands and forearms when the arms 7 and gloves 8 are in use. I also prefer to supply straps 40 to hold the sleeves more tightly around the wrists. The armholes consist of slits 39, as shown in Fig. 7, between the side body air chambers 2.

Pockets 32 are provided in the lining 30 as also may be an air pump 33 connected by piping 34, arranged between said lining 30 and air chambers 2. Each air chamber is 100 provided with a non-return valve 35, shown in detail in Figs. 12 and 13. A clasp 36, shown in detail in Fig. 14, may be placed on the piping 34, leading into either of the air chambers, so that any of the said check 105 valves may be immediately cut off in the event of an air chamber becoming defective. Instead of using a pump as above described the piping 34 may be continued up into the helmet in the same way as the leg air pipes 110 9, and the body air chambers also inflated from the mouth.

It is understood, moreover that variations and modifications may be made to the foregoing provided the said variations and modifications fall within the scope of what I claim.

What I claim as my invention and desire to secure by Letters Patent is:

1. In a life saving garment, a helmet having an air inlet opening, a pipe located in the helmet and having an opening communicating with the air inlet opening, said pipe having open ends, and means for closing the ends of said pipe. 120

2. In a life saving garment, a helmet having an air inlet opening, a pipe located in the helmet and having an opening communicating with the air inlet opening, said pipe having open ends, slides connected to said 130

pipe and carrying covers for the open ends of the same, springs for normally retaining said covers in open position, and means for closing said covers.

5. 3. In a life saving garment, a helmet having an air inlet opening, a horizontally extending open ended pipe located in said helmet and having an opening communicating with the air inlet opening, covers for the open ends slidably mounted on the pipe, means for normally holding the covers in open position, and means for closing said covers.

10 4. A life saving device comprising a helmet having an air chamber arranged round the top, sides, and back thereof, and means for inflating or deflating said air chamber, a body portion comprising a series of vertical

air chambers arranged between a warm inner lining and a waterproof outer covering, 20 means for inflating said body air chambers, means for cutting off the air supply from any air chamber that may prove defective, and a substantially waterproof inner and outer closure, in combination with leg portions each having an air chamber and independent means for inflating and deflating same, said leg portions terminating in boots and sleeves and gloves arranged from said body portions, access being had to said sleeves through slits provided between said body air chambers. 25 30
